MOP

Clarence J. Ostieck, Minneapolis, Minn.

Application November 17, 1933, Serial No. 698,410

6 Claims. (Cl. 15—147)

My invention relates to mops and particularly to the type of mop known as a dust mop which comprises a swab holder constructed of a coil spring arranged in the form of a loop and secured to the handle.

An object of the invention resides in providing a mop by means of which the ends of the coil spring may be quickly and easily attached to the handle and detached when the occasion arises.

10 An object of the invention resides in providing a supporting structure for the mop including a support attached to the handle and in further providing means carried by the support and formed with threads for engagement with the convolutions of the coil spring to hold the ends thereof attached to the support.

A still further object of the invention resides in constructing the support with one or two shanks and in providing threaded members on 20 said shanks adapted to engage the convolutions of the coil spring.

Another object of the invention resides in constructing one of said threaded members revoluble with respect to the shank whereby the same may 25 be rotated to bring the threads thereof into engagement with the convolutions of the coil spring.

A feature of the invention resides in constructing the support from a rod bent to provide angularly disposed shanks and in further employing 30 an attaching member consisting of two parts overlying said rod intermediate the shanks thereof and upon both sides of the rod, said attaching member being secured to the shank and to the end of the handle.

35 An object of the invention resides in constructing the supporting structure with an attaching member consisting of two parts, each of said parts having portions overlying the handle on the opposite sides thereof and secured thereto and secured to the support.

Another object of the invention resides in employing a threaded sleeve revoluble upon one of the shanks of the support for engagement with the convolutions of the coil spring.

45 A feature of the invention resides in constructing the shank with a reduced end, said end having a head mounted thereon for engagement with the coil spring and in constructing said sleeve with threads upon the interior thereof spaced from the head and adapted to engage the convolutions of the spring upon the exterior thereof.

50 Another object of the invention resides in constructing said head so as to restrain said sleeve from axial movement in one direction and in further providing means for further restraining the

axial movement of said sleeve in the opposite direction.

A still further object of the invention resides in reducing the end of the sleeve to form a shoulder and in rotatably mounting the sleeve upon 5 the reduced end of said shank and against said shoulder and in further riveting over the reduced end of the shank for the purpose of retaining the sleeve thereon.

A feature of the invention resides in forming 10 a flange on the end of the sleeve by means of which the sleeve may be rotated to cause the same to be brought into operative position.

Other objects of the invention reside in the novel combination and arrangement of parts and 15 in the details of construction hereinafter illustrated and/or described.

In the drawings:

Fig. 1 is a plan view of a dust mop with the swab removed and illustrating an embodiment 20 of my invention.

Fig. 2 is an elevational view of the structure shown in Fig. 1.

Fig. 3 is a plan sectional view of a portion of the structure shown in Fig. 1 and drawn to a 25 larger scale.

Fig. 4 is a cross sectional view taken on line 4—4 of Fig. 3.

Fig. 5 is a plan view of a modification of the invention with the swab holder and one of the 30 swab holder supports shown in section.

Fig. 6 is a view similar to Fig. 4 of the structure shown in Fig. 5.

In the construction of dust mops and particularly the type of mop in which the swab may be 35 removed by the user whenever desired, considerable inconvenience and difficulty has been experienced in the application of the supporting structure for the swab to the handle. The present invention provides a simple and practical 40 device in which the swab may be readily and easily applied to or removed from the mop.

For the purpose of illustrating the application of my invention I have shown in Fig. 1 a handle 10 which may be constructed of wood or any other 45 suitable material. The said handle is preferably round and is formed with a tapered end 11 to which the swab of the mop is attached.

The mop proper consists of a swab holder 12 which is constructed from spring wire coiled to 50 provide a number of convolutions 26 which form a coil spring indicated in its entirety by the reference numeral 13. This coil spring is adapted to be bent into a loop as shown in Fig. 1 and is attached to the handle 10 as will be presently 55

described in detail. The swab, not shown in the drawings, is constructed with a hem or similar construction through which the said coil spring is inserted and by means of which the swab is attached to the holder. Inasmuch as the swab does not form any particular feature of the invention, the same has not been shown in the drawings, though it can readily be comprehended that any construction, such as is now in common use and such as is disclosed in Patent No. 1,849-150, may be used for the purpose. The swab holder 10 being constructed as a coil spring is flexible and permits of bending the swab to cause the same to follow the contour of the surface on which it is applied and permits of readily manipulating the mop in crowded corners and in localities where a rigid holder could not be effectively used.

The swab holder is attached to a supporting structure referred to by the reference character 14 which supporting structure consists of a support 15 formed of a cylindrical rod bent to provide two angularly disposed portions 16 and 17 which serve as shanks and a connecting portion 18 between the same. In the form of the invention shown in Figs. 1 to 4, the shanks 16 and 17 are reduced in diameter as designated at 19 and 21. Upon the reduced portion 21 is mounted a head 22 which is bored at 23 to receive the same. This head is secured to the said reduced portion of the shank through a pin 24. The exterior of the head 22 is constructed with threads 25 which are adapted to screw into the convolutions 26 of the coil spring 13. It can readily be comprehended that when the coil spring 13 is free, one end 27 of the same may be screwed upon the head 22 and so held attached to the support 15.

For attaching the other end 28 of the coil spring 13 to the support 15, a construction is employed which is best shown in Fig. 3. Mounted upon the reduced end 19 of the shank 16 of the support is another head 29 which is free from the threads and which is bored as indicated at 31 to fit over the same. This head is secured to the shank through a pin 32. The outer diameter of the head 29 is such that the same fits freely within the interior of the coil spring 13, the same serving as a guide for guiding the coil spring for sliding movement into position upon the support 15. In conjunction with the head 29 a sleeve 33 is employed which is constructed upon the interior thereof with threads 34 adapted to screw upon the exterior of the convolutions 26 of the end 28 of coil spring 13. This sleeve is further constructed with a flange 35 which is rotatably mounted upon the shank 16 immediately in back of the head 29. The head 29 is slightly larger in diameter than the shank 16 to form a shoulder 37 adapted to be engaged by the flange 35. By means of this construction the sleeve 33 is rotatably supported on the shank and the same held from axial movement in one direction. For restraining the sleeve 33 from axial movement in the opposite direction, a pin 38 is employed which passes through the shank 16 and is secured thereto and which engages the end of flange 35. The outer surface of the sleeve 33 is knurled as designated at 39 by means of which the same may be readily rotated by the user when it is desired to attach the end 28 of the coil spring to the swab holder.

The supporting structure 14 further includes two attaching members 41 and 42. These two attaching members are provided with curved por-

tions 43 and 143 which fit about the tapered end 11 of handle 10. Two rivets 44 and 45 pass through both of the members 41 and 42 and hold the same rigidly attached to the handle. The ends of the members 41 and 42 are bent to fit about the connecting portion 18 of the support 15. For assisting in holding the said parts attached together, the member 15 is flattened as designated at 46, whereby the ends 47 and 48 may be firmly seated upon the connecting portion 18. A rivet 49 passes through the portions 47 and 48 and also the connecting portion 18 of support 15, whereby the members 41 and 42 are firmly attached to the support. The end portions 51 and 151 of the attaching members 41 and 42 engage the outer surface of the connecting portion 18 of support 15 and help to hold the said support from lateral movement with respect to the attaching members 41 and 42.

Although I have described the members 41 as attached to the member 15 through a rivet, it can readily be comprehended that the two attaching members 41 and 42 may be secured thereto in any other suitable manner.

In the description of the invention, a stationary threaded member has been shown on one of the shanks of the support, while a revoluble threaded member has been shown on the other.

The use of my invention is as follows: When the mops are sold the supporting structures 14 are attached to the handles 10 and the swab holders and swabs furnished separate. When desired for use one of the coil springs 13 which is normally straight, is threaded upon the threaded head 22. While the same is still straight, said coil spring is threaded through the hem or tubular portion of the swab and the other end 28 thereof is bent toward the support 15 and inserted over the end of the head 29. Sleeve 33 is next rotated through engagement with the knurled portion 29 thereof and the threads 34 of said sleeve caused to engage the convolutions 26 of the coil spring 13. This draws the end of the coil spring inwardly into the interior of said sleeve until the extreme end of the coil spring 45 engages the flange 35. During such movement the coil spring is drawn over the head 29 which together with the sleeve 33 causes the said end of the coil spring to be firmly and securely held in position. The mop is now in position for use and may be used in the customary manner.

In Figs. 5 and 6 I have shown a modification of the invention. In this form of the invention two supports 52 and 53 are provided which are constructed with cylindrical shanks 54 and 55. These shanks are formed at their ends with curved portions 56 and 57 which fit over the tapered end 11 of handle 10. The two portions 56 and 57 are secured to the said handle through rivets 58 and 59 similar to the rivets 44 and 45 of the other form of the invention. The two shanks 54 and 55 are constructed with reduced ends 61 and 62 which provide shoulders 63. Two sleeves 64 and 65 are revoluble upon the said reduced portions of the shanks 54 and 55 and are seated at one end against the shoulders 63, being restrained from longitudinal movement toward the handle thereby. The other ends of the said sleeves are held from longitudinal movement in the opposite direction through heads 66 formed on the ends of the reduced portion 61 of said shanks by riveting over the same. The sleeves 64 are constructed with external threads 67 and 167 which screw into the interior of the coil spring 13 engaging the convolutions 26 upon the 75

interior thereof. The sleeve 64 is constructed with a flange 68 at the end thereof which flange is knurled on the exterior as designated at 69 to permit of readily rotating the same. By means of this construction, the threads 67 and 167 can be screwed into convolutions 26 of the spring 13 and the end of the spring attached to the support 52.

The use of the invention shown in Figs. 5 and 10 6 is similar to that previously described. One end of the spring 13 may be first screwed upon one of the sleeves 64 or 65 and the swab then applied. The other sleeve is then rotated through the knurled flange 68 and screwed into the reduced end of the spring on which the swab is mounted causing the threads thereof to engage the convolutions of the other end of the spring.

My invention is highly advantageous in that an extremely simple and practical device is provided, whereby the ends of the coil spring used as a swab holder may be easily and securely attached to the supporting structure therefor. A swab holder attached through the means shown is readily applied and when once applied, 25 remains permanently in position until it becomes necessary to remove the swab from the swab holder. The application of the swab holder to the support is accomplished through simple manipulation such as is readily understood by any 30 person capable of using the mop. The invention can be constructed at a nominal cost and by simple manufacturing methods. My invention is extremely rigid and substantial in construction and has all of the advantageous and 35 desirable characteristics of similar mops constructed in other different ways.

Changes in the specific form of my invention, as herein disclosed, may be made within the scope of what is claimed without departing from the spirit of my invention.

Having described my invention, what I claim as new and desire to protect by Letters Patent is:

1. In a mop, a handle, a swab holder comprising a coil spring arranged in the form of a loop, a support carried by said handle adapted to support one end of said coil spring, a member rotatable on said support, said member having threads adapted to engage the convolutions of said spring at its other end for detachably supporting the other end of said spring and means on said support for holding said member from axial movement.

2. In a mop, a handle, a swab holder comprising a coil spring arranged in the form of a loop, a support carried by the handle and having a shank, a sleeve revoluble on said shank, means for holding said sleeve from axial movement relative to the shank, threads formed upon the exterior of said sleeve and adapted to engage with the convolutions of the spring upon the interior

of the spring at one end for detachably supporting the spring and means carried by the support for supporting the spring at its other end.

3. In a mop, a handle, a swab holder comprising a coil spring arranged in the form of a loop, a support carried by the handle and having a shank, a sleeve revoluble on said shank, means for holding said sleeve from axial movement relative to the shank, said sleeve being constructed with a bore of larger diameter than said shank and being provided upon the interior thereof with the threads adapted to engage the convolutions of the spring at one end, said sleeve extending along said shank and said shank serving to engage the interior of the spring for guiding the same into coaction with the threads of the sleeve, and means carried by the support for supporting the spring at its other end.

4. In a mop, a handle, a swab holder comprising a coil spring arranged in the form of a loop, a support carried by the handle and having a shank, said shank being reduced at one end to form a shoulder, a sleeve revoluble on the reduced end of said shank and seated at one end against said shoulder, the extreme end of said shank being riveted over to hold the sleeve in place upon said shank, threads formed on said sleeve for engagement with the convolutions of the spring at one end to hold the same attached to the support and means carried by the support for supporting the spring at its other end.

5. In a mop, a handle, a swab holder comprising a coil spring arranged in the form of a loop, a support carried by the handle and having a shank, an enlarged head on the end of said shank adapted to fit within the interior of said coil spring, a sleeve revoluble upon said shank and held from axial movement in one direction by said head, means secured to said shank for holding said sleeve from axial movement in the other direction, said sleeve being larger than said spring and being formed upon the interior thereof with threads adapted to engage the convolutions of the spring to hold the spring at one end in position upon the shank and means carried by the support for supporting the spring at its other end.

6. In a mop, a handle, a swab holder comprising a coil spring arranged in the form of a loop, a supporting structure attached to the handle and including two shanks angularly disposed relative to one another, a threaded member rotatably mounted on one of said shanks for engagement with the convolutions of the spring at one end for detachably securing said end of the spring to the supporting structure, means for holding said threaded member from axial movement relative to the shank, and means on the other shank for securing the other end of the spring to the supporting structure.

CLARENCE J. OSTDIEK.
